US0D1068826S

(12) **United States Design Patent** (10) Patent No.: **US D1,068,826 S**
Gu (45) Date of Patent: ** Apr. 1, 2025

(54) **DISPLAY SCREEN OR PORTION THEREOF WITH GRAPHICAL USER INTERFACE**

(71) Applicant: **HUAWEI TECHNOLOGIES CO., LTD.**, Guangdong (CN)

(72) Inventor: **Guosheng Gu**, Shenzhen (CN)

(73) Assignee: **HUAWEI TECHNOLOGIES CO., LTD.**, Shenzhen (CN)

(**) Term: **15 Years**

(21) Appl. No.: **29/856,682**

(22) Filed: **Oct. 17, 2022**

(30) **Foreign Application Priority Data**

Apr. 18, 2022 (CN) 202230215680.4

(51) **LOC (15) Cl.** **14-04**

CLAIM

The ornamental design for a display screen or portion thereof with graphical user interface, as shown and described.

DESCRIPTION

The single FIGURE is a front view of a display screen or portion thereof with a graphical user interface showing my new design.

The outermost dash-dotted broken lines in the FIGURE illustrate the display screen or portion thereof and form no part of the claimed design. The dotted broken lines in the FIGURE illustrate portions of the graphical user interface that form no part of the claimed design.

1 Claim, 1 Drawing Sheet
